CASING PERFORATOR

Charles B. Margrave, Los Angeles, Calif., assignor
of one-half to Albert I. Breslow, Los Angeles,
Calif.

Application January 11, 1937, Serial No. 120,026

10 Claims. (Cl. 164—0.4)

My invention pertains to a perforator for perforating well casing such as the casing of oil wells and provides a type of perforator which gives a clean cut at the perforation and forces the slit 5 metal of the casing outwardly at the perforation developing a slight fin at the top of the perforation which restricts the entrance of sand with oil into the casing. Another feature of my invention is that the perforator which has perforating 10 cutters causes these cutters to have a sliding movement transverse to the axis of the casing and in which the perforating cutters or cutter tools thus have a sliding motion radially of the casing and as two tools are employed, these are 15 diametrically opposite. Another feature of my invention is developing a force to force the tools through the casing by a toggle action, this being produced by a slight lowering of a drill string or the like to force the perforator tools outwardly, 20 these being supported by a portion of a string of drill pipe or similar tools resting on the bottom of the well and extending upwardly to the desired position in which it is desired to perforate the casing.

25 Considered in more detail, a further object and feature of my invention is in the construction of toggle actuated cutter tools operating in diametrically opposite slots, each of which is connected to toggle links, these being pivoted to a common 30 head and such head being slidably arranged in a guide block. When this guide block is connected to the upper portion of the string of drill pipe, the assembly may be lowered into the well and when the bottom of the string below the blocks 35 supporting the cutting tools contacts the bottom of the well, the further slight lowering of the drill string due to the weight causes the movable head having the toggle links to develop a further downward movement, the links thus pressing the cutter tools outwardly diametrically opposite and thus perforating the casing. A further detail 40 feature of my invention is in the shape of the cutter tools which preferably have a flat or straight bottom edge, an upwardly and inwardly sloping perforating surface with slightly beveled 45 side edges. This causes the cutter tool to make a clean cut at the bottom of the perforation, this being a sheer cut on the casing. A sheer cut is also given at the sides of the perforation so that 50 an upper protruding lip is bent outwardly at the top of the perforation. This lip tends to prevent sand settling through the opening of the perforation into the casing. Another characteristic of the type of perforator used coupled with the sliding motion is that the perforator may be used to

crack cement which may be on the outside of the casing. This is an advantage as it sometimes happens that in cementing off a water bearing strata that the cement will also cut off a portion of the oil bearing sands. With my type of perforators the casing may not only be perforated but also the cement on the outside cracked to permit inflow of oil.

My invention is illustrated in connection with the accompanying drawings, in which:

Fig. 1 is a vertical section through my invention taken on the line 1—1 of Fig. 3 in the direction of the arrows showing the perforator cutters and toggle links in elevation and also the plug and rod to which these are connected shown in elevation. In Fig. 1 the cutters are retracted.

Fig. 2 is a section similar to Fig. 1 with the cutters forced outwardly by the downward movement of the toggle links.

Fig. 3 is a horizontal section on the line 3—3 of Fig. 2 taken in the direction of the arrows.

Fig. 4 is a detail vertical section on the line 4—4 of Fig. 2 in the direction of the arrows showing one of the cutters and the cutter guide opening.

Fig. 5 is a horizontal section on the line 5—5 of Fig. 2 on a reduced scale.

Fig. 6 is a detail plan of one of the perforating cutters removed from the assembly.

In my invention a toggle guide block assembly 30 designated by the numeral 11 consists of a lower block 12 which has a flat upper surface 13 transverse to the axis of the tool, the side wall 14 is cylindrical merging by a rounded corner 15 to a flat bottom surface 16 from which an integral 35 solid rod 17 extends downwardly. The upper block member 20 is heavy and rests on the flat surface 13 of the lower block. This however has two diametrically opposite guide slots 22 defined by the two opposite vertical edges 23, the top 40 edge 24 and the surface 13 of the lower block forming the bottom wall of the guide opening. This block is also cylindrical as to its side wall 25 and has rounded corners 26 merging with the flat top surface 27. Centrally positioned in the 45 upper block there is a large circular bore 28 and below this there are diverging recesses 29 having a sloping upper surface 30 merging with the upper surface 24 of the guide openings 22, this slope being to accommodate the toggle lengths hereinunder detailed. These recesses are considerably wider in a transverse measurement indicated at 31 in Fig. 3 to accommodate the toggle links as hereinunder detailed. The two blocks are held together by utilizing a strong and heavy ring 32 50

which rests on the flat top 27 of the upper block. This ring has a peripheral wall 33 preferably slightly smaller than the diameter of the upper block 28 as to its cylindrical wall 25 and has a 5 central opening 34 which is smaller in diameter than the bore 28.

A heavy cylindrical plug 40 having an integral rod 41 preferably cylindrical is part of the toggle actuating assembly, the plug being located in the 10 large bore 28, this plug having an upper shoulder 42 engaging underneath the heavy ring 32. This ring and the upper and lower blocks are securely bolted together by a series of longitudinal bolts 43. Thus by suspending the rod 41 the plug 40 15 may engage underneath the ring 32 and suspend the whole block assembly 11 and a portion of a drill string as hereinunder described, secured to the lower end of the solid rod 17.

The plug 40 has a recess 44 from its undersurface 20 face 45 and in this is fitted the upper end of the toggle plate 46. This plate is rectangular in horizontal section as indicated in Fig. 3 and has a shoulder 47 bearing on the undersurface 45, this plate being secured by a pin 48 or the like extending 25 through the plug 40 and through an opening in the portion of the plate inserted in the recess 44.

The toggle assembly 50 has two pair of parallel toggle links 51. The upper end 52 of each pair is pivoted to the toggle plate 46 by substantial toggle 30 pins 53. The lower ends 54 are pivoted also by substantial pivot pins 55 to the perforating cutting tools 56. Such perforating tools have a flat lower surface 57, parallel sides 58 and a flat top 59. There is a sloping cutting end 60 with a sharp 35 forward cutting point 61. The two side edges of the sloping face of the cutter are slightly beveled as indicated at 62 and also adjacent the sharp edge 61 there may also be a slight bevel 63.

The manner of assembling the tool in a string of 40 drill pipe may be in any suitable way, the manner illustrated showing an upper "sub" 70, the upper end of the solid rod 41 being threaded therein as indicated at 71, these being tight threads not intended to unscrew in disconnecting stands of the 45 drill string. This sub is shown as having a taper threaded box 72 to which a pin of a tool joint coupling may be connected, this forming part of the drill string with the tool inserted in the string. As it is usually necessary to perforate the casing 50 at some distance above the bottom of the well, the lower solid rod 17 is shown as threaded into a lower "sub" 75, this having a tight fitting threaded section 76. This "sub" may also have a pin on its lower end for connecting to the lower 55 part of the drill string by a tool joint coupling and below this there may be a further portion of the drill string indicated at 77. This is shown as resting on the bottom of the well hole indicated at 78. The bore of the hole is indicated at 79 and 60 the casing at 80. It sometimes occurs that outside of the casing there is a body of cement indicated at 81, and although the cement is usually for the purpose of cutting off water from the well, sometimes this cement is found to be in an oil 65 bearing strata.

In the operation of my invention it will be understood that a survey of the well has made it known what locality of the casing is to be perforated, therefore the drill string is made up with 70 the perforating tool in the proper place so that the lower end of the string may rest on the bottom of the hole. In lowering, the plug 40 engages the ring 32 and carries the weight of all of the string below the solid rod 41. While the string is being 75 lowered the toggle links are in the upper position

and the tools are retracted as shown in Fig. 1. When the lower end of the drill string as indicated at 77 contacts the bottom of the hole and the upper part of the string is lowered, the weight of this forces the rod 41, the plug 40 and the head 5 carrying the toggle links 54 outwardly. This toggle action forces the cutter tools in an outward direction and thus causes the perforation of the casing. On account of the perforator cutters having a sharp cutting edge 61 at the bottom and 10 a bevel face, a straight horizontal sheer cut is made by the cutter and also the side edges of approximately a straight cut, this causing a lip indicated at 82 to be forced outwardly above the 15 perforation. Such lip tends to restrict the flow of sand into the casing. The perforating cutters are also operative to crack any cementing wall on the outside of the casing and thus allow a flow of oil through such cement.

Various changes may be made in the details of 20 the construction without departing from the spirit or scope of the invention as defined by the appended claims.

I claim:

1. A casing perforator comprising in combination a substantial block assembly having diametrically opposite straight transverse guide openings and a central bore connected thereto, perforators rectilinearly slidably mounted in the 30 openings, a plug slidably mounted in the bore, toggle links, means connecting the toggle links between the plug and the perforators, a supporting means connected to the lower end of the block assembly for supporting the block in a desired position in a well casing, means attached to the plug for connection to a string of drill pipe for raising and lowering the plug whereby when the plug is elevated the perforators are forced outwardly to perforate the casing. 40

2. A casing perforator comprising in combination a block assembly having a lower block and an upper block, said blocks having contiguous horizontal surfaces with a pair of diametrically opposite straight radial transverse guide openings, the upper block having a central bore, a plug having a shoulder and slidably in the said bore, a retaining means on the upper block, bolts through said retaining means and the upper and lower blocks for retaining the block assembly, the said 50 retaining means being adapted to engage the upper end of the plug, perforators rectilinearly slidably mounted in the guide openings, toggle links pivotally connected thereto, means connecting the upper ends of the toggle links to the said plug, a supporting means connected to the lower block for retaining the block assembly in the desired position in a well casing, means connected to the plug for attachment to a string of drill pipe whereby the block assembly may be lowered in 55 a casing and when the supporting means supports the block assembly in the desired position the continued downward movement of the plug forces the perforators outwardly laterally to perforate 60 the casing. 65

3. A casing perforator as claimed in claim 2, the supporting means comprising a rod connected to the lower block, a sub connected thereto, said sub being adapted to engage the bottom of the well hole. 70

4. A casing perforator comprising in combination a block assembly having a lower block with a horizontal upper surface, an upper block with a complementary surface and a pair of diametrically opposite straight radial guide openings ex- 75

tending upwardly from the lower surface of the upper block, the upper block having a central bore, a ring on the upper block, bolts extending through the ring and the upper and lower blocks, 5 a plug slidably mounted in the said bore, perforators rectilinearly slidably mounted in the guide openings and bearing on the upper surface of the lower block, toggle links connected to the perforators, means pivotally connecting the upper 10 ends of the toggle links to the said plug, the plug having a shoulder engaging the under side of the said ring, means for attaching the plug to a string of drill pipe, a supporting means connected to the lower block for supporting the block assembly 15 in a desired position in a well casing, the said block assembly and the supporting means being adapted to be lowered into a well suspended from the plug and with the perforators retracted, a downward movement of the plug when the block 20 assembly is held stationary being adapted to force the perforators diametrically outwardly to perforate the casing.

5. A casing perforator as claimed in claim 4, the perforators having a flat lower surface terminating in a horizontal outer cutting edge, an upwardly sloping cutting end from the cutting edges whereby in perforating the casing an outwardly projected lip is formed above the perforation.

6. A casing perforator as claimed in claim 4, the means connecting the toggle links to the plug comprising a toggle plate connected to the lower end of the plug, the upper ends of the toggle links being pivotally connected to the said plate.

7. A casing perforator comprising in combination a block assembly having a lower block with a horizontal upper surface, a rod projecting downwardly and having means for connection to a lower sub, an upper block having a flat lower surface contacting the upper surface of the lower block, the upper block having diametrically opposite straight radial guide openings forming two guide slots defined by opposite vertical sides, a horizontal top and the upper surface of the lower block, the upper block having a central bore connecting with the said slots, a ring on the top of the upper block and having an opening smaller than the said bore, bolts connecting the two blocks and the ring, a plug slidably mounted in the said bore and having a toggle plate connected thereto at the bottom, a pair of toggle links pivotally connected to said plate, a pair of perforators in the said slots and pivotally connected to the lower end of the toggle links, means connecting the plug and adapted for attachment to the lower end of a string of drill pipe whereby the assembly of the blocks and the lower sub may be lowered

into a well, the ring engaging the said plug and thereby retracting the perforators, the said sub on engaging the bottom of the well hole forming a solid support for the block assembly whereby the continued downward movement of the plug 5 forces the perforators rectilinearly outwardly to perforate the casing.

8. A casing perforator as claimed in claim 7, the perforators being rectangular in vertical cross-section and having a flat lower surface with 10 a horizontal outside cutting edge and upwardly sloping cutting ends, the said ends on each side having a slight bevel whereby on perforating a casing a clean horizontal sheer cut is formed at the bottom of the perforation and lips are outwardly bent at the upper part of the perforation. 15

9. A casing perforator comprising in combination a block assembly having a lower block with a horizontal upper surface, an upper block having a complementary lower horizontal surface 20 with a pair of diametrical straight radial slots in its lower surface defining with the upper surface of the lower block straight radial guide openings rectangular in cross section, the upper block having enlargements at the inner end of said slots 25 and a central circular bore connecting to said enlargements, a ring on the upper end of the upper block, bolts through the ring and the two blocks, a cylindrical plug mounted in the bore and having an upper shoulder engaging the ring, perforators rectangular in cross section slidably rectilinearly transversely in the said slots, toggle links having their lower ends pivotally connected to the inner ends of the perforators, means pivotally connecting the upper ends of the toggle links to 30 the said plug, the lower block having a solid lower rod of much smaller diameter than the block extending downwardly and a lower sub connected to said lower rod, the plug having a solid upper rod extending upwardly through the ring and having means for connection to a string of drill pipe whereby the assembly may be lowered into a well, the shoulder of the plug engaging the said ring and when the lower sub contacts the bottom of the well hole the continued downward movement of the plug forces the perforators outwardly. 35

10. A casing perforator as claimed in claim 9, the means connecting the toggle links to the plug comprising a toggle plate flat on its two opposite sides and connected to the lower end of the plug, 50 the toggle links comprising a pair of links pivotally connected to each perforator and pivotally connected on the opposite flat sides of the toggle plate.

C. B. MARGRAVE. 55
